HOLDER FOR HAMBURGERS OR THE LIKE

Frank M. Kay, 604 W. Burleson, Marshall, Tex. 75670
Filed Apr. 24, 1967, Ser. No. 6,799

Term of patent 14 years

(Cl. D44—10)

FIG. 1 is a perspective view of a holder for hamburgers or the like showing my new design;

FIG. 2 is a front elevational view; and

FIG. 3 is a sectional view taken on the line 3—3 of FIG. 2.

The broken line showing is for illustrative purposes only.

I claim:

The ornamental design for a holder for hamburgers or the like, as shown and described.
